UNITED STATES PATENT OFFICE.

ADELARD BOUCHER, OF WINCHESTER, MASSACHUSETTS, ASSIGNOR OF ONE-HALF TO
ALFRED G. PELLETIER, OF WINCHESTER, MASSACHUSETTS.

PORTABLE COMBINATION SAWING AND GRINDING MACHINE.

Application filed January 19, 1925. Serial No. 3,247.

To all whom it may concern:

Be it known that I, ADELARD BOUCHER, a citizen of Canada, residing at Wincendon, in the county of Worcester and State 5 of Massachusetts, have invented certain new and useful Improvements in Portable Combination Sawing and Grinding Machines, of which the following is a specification.

This invention relates to a portable machine for use in homes or small workshops for such work as grinding, sawing or the like, the invention having for an object the provision of a novel and simple machine of this sort, in which a common operating 10 means is provided for the saw and grindstone and is arranged for convenient selective engagement with either of these implements.

For further comprehension of the invention, and of the objects and advantages 20 thereof, reference will be had to the following description and accompanying drawing, and to the appended claims in which the various novel features of the invention are 25 more particularly set forth.

Fig. 1 of the drawing is a side view of my improved machine.

Fig. 2 is a transverse vertical sectional view taken on the line 2—2 of Fig. 1.

Fig. 3 is a fragmentary longitudinal sectional view showing the saw clutch.

Fig. 4 is a detail view showing the handle engaged with the initial shaft.

As here embodied my improved machine 35 comprises a flat rectangular base 10 from which a bifurcated standard 11 projects upwardly. Located between the legs of this standard is a train of gears, as here shown four in number, positioned one above 40 the other and which are numbered respectively from top to bottom, 14, 15, 16, and 17. The top gear 14 is fixed on a shaft 20 that has squared ends 20' projecting from the standard to receive a handle 21. The 45 second gear 15 acts as an idler and is suitably supported in the standard, while the gears 16 and 17 drive the grindstone 23 and the circular saw 24 respectively.

The gear 16 is formed with a hub extension 16' that projects through one leg of the standard and has an integral clutch element 26 thereon adapted to engage a clutch collar 27 feathered as at 28 on the shaft 29 that supports the grindstone 23, this shaft

extending freely through the hub extension 55 of the gear, a projection 11' from the standard serving to support the outer end of the shaft 29 on which the grindstone is fixed.

The gear 17 is fixed on a shaft 32 that extends at one end through the standard 11 60 and has mounted thereon a clutch collar 33 adapted to be moved into and out of engagement with a clutch element 34 fixed to the saw 24, the saw and clutch element 34 being loose on the shaft 32. For shifting the 65 clutch collar 33 I provide a rod 36 that extends through a longitudinal boring 37 in the shaft 32 and has fixed to one end a transverse pin 38 that extends through a pair of longitudinal slots 39 in the shaft 32 and is 70 fixed at its ends in the collar 33. This arrangement also provides a feather connection between the collar 33 and the shaft 32 as will be apparent.

The clutch collars 27 and 33 are arranged 75 to be shifted inversely in unison, and to this end a lever 42 is fulcrumed between its ends to a bracket 43 projecting from the standard 11, and has a pair of pins 44 thereon, one of which engages in a circumferential groove in the collar 27 and the other in a grooved collar 45 fixed to the projecting end of the rod 36. The lever 42 extends upward beyond the collar 27 and has attached to its upper end one end of a 80 tension spring 47 whose other end is connected to the standard 11, this spring normally urging the lever to position with the grindstone 23 in operative relation to the drive mechanism and the saw 24 out of operative relation, this being the position 85 shown in Fig. 1 of the drawing.

Fulcrumed between its ends as at 50 to the side of the standard 11 is another lever 51 whose lower end projects behind the 95 upper end of the lever 42, while its upper end is adjacent the end of the shaft 20. When the saw is to be used, the handle is removed from the end of the shaft on which it is shown and secured upon the other end 100 of the shaft. When the handle 21 is pushed onto the said other end of the shaft it moves the lever 51 to shift the levers 42, and thereby disengage the clutch collar 27 of the grindstone and engage the clutch collar 33 105 of the saw. The handle 21 may be locked in position on either end of the shaft by means of a set screw 54 threaded through

the handle and engaged in a socket 54 of which there is one in each end of the shaft 20.

Having thus described my invention, 5 what I claim as new and desire to protect by Letters Patent of the United States is as follows:—

1. A machine of the type set forth comprising a standard, a series of meshing gears mounted in said standard one above the other, manual drive means applied to the top gear, shafts co-axial with the two lower gears projecting respectively on opposite sides of the standard, and a grindstone 15 and a saw mounted on the respective shafts, clutch elements for engaging the respective gears with their shafts, and means for shifting said clutch elements inversely in unison.

20 2. A machine of the type set forth com-

prising a standard, a series of meshing gears mounted in said standard, one above the other, a shaft on which the top gear is fixed said shaft having squared ends projecting from the standard, shafts co-axial 25 with the two lower gears projecting respectively on opposite sides of the standard, tools on said shafts, shiftable clutch elements on the respective shafts for operatively engaging the same with the said tools, and means for shifting said clutch elements inversely in unison, including a lever projecting at one end adjacent one of the squared ends of the upper shaft, to be engaged and moved by a handle placed on 30 said shaft.

In testimony whereof I have affixed my signature.

ADELARD BOUCHER.
